CLAIM

The ornamental design for a display screen portion with graphical user interface, as shown and described.

DESCRIPTION

The present application is also related to U.S. Design patent application Ser. No. 29/623,844, filed Oct. 27, 2017; U.S. Design patent application Ser. No. 29/623,815, filed Oct. 27, 2017; U.S. Design patent application Ser. No. 29/679,663, filed Feb. 8, 2019; U.S. Design patent application Ser. No. 29/623,820, filed Oct. 27, 2017, now U.S. Design Pat. No. D847,858; U.S. Design patent application Ser. No. 29/680, 898, filed Feb. 21, 2019; U.S. Design patent application Ser. No. 29/623,826, filed Oct. 27, 2017; and U.S. Design patent application Ser. No. 29/623,833, filed Oct. 27, 2017, the entire disclosures of which are incorporated herein by reference.

FIG. 1 is a front view of a first image in a sequence for a display screen portion with graphical user interface, according to our design.

FIG. 2 is a second image thereof;

FIG. 3 is a third image thereof;

FIG. 4 is a fourth image thereof; and,

FIG. 5 is a fifth image thereof.

The dash-dot lines show the display screen portion and form no part of the claimed design. All other broken lines show portions of the graphical user interface and form no part of the claimed design.

The appearance of the image sequentially transitions between FIGS. 1-5.

The process or period in which one image transitions to another image forms no part of the claimed design.
